UNITED STATES PATENT OFFICE.

GEORGE H. HESS, OF LA GRANGE PARK, ILLINOIS.

METHOD OF TREATING PIECES OF MATERIAL OF NON-UNIFORM MOISTURE CONTENT TO AN IMPREGNATING FLUID.

1,241,973.

Specification of Letters Patent.

Patented Oct. 2, 1917.

Application filed May 17, 1917. Serial No. 169,265

To all whom it may concern:

Be it known that I, GEORGE H. HESS, a citizen of the United States, residing at La Grange Park, in the county of Cook and

5 State of Illinois, have invented a new and useful Method of Treating Pieces of Material of Non-Uniform Moisture Content to an Impregnating Fluid, of which the following is a specification.

10 My invention relates to the process of treating particles of non-uniform moisture-content to an impregnating fluid, generally, but more particularly to the treatment of wood fiber, as for example wood chips, in 15 the manufacture of paper pulp, this being the use for which my invention was more particularly produced and which treatment involves the subjection of the wood chips to the action of a chemical solution into which 20 the chips are introduced in accordance with common practice.

It is desirable in the treatment of materials to impregnating fluids, as for example wood chips in the digesting or "cooking" operation, that the particles of materials on introduction into the impregnating fluid be of substantially low, and substantially uniform, moisture-content in order that the action of the fluid upon the fibers of the particles be uniform, a result which cannot be accomplished unless the particles present a substantially uniform moisture-content, owing to the fact that the existence of the moisture in the particles dilutes the impregnating fluid in the proportion in which the moisture is present, and if the dilution is not uniform the action of the fluid is consequently not uniform, this resulting in under, or over, treatment and the production of an 40 imperfect or non-uniform product. One of the disadvantages resulting from the chemical treatment of wood chips for making paper pulp, when the chips are not of substantially uniform moisture-content, is that a large 45 portion of the chips are subjected either for too long, or too short, a time, to the digesting chemicals, in the former case destroying the fibers of these chips because of over-treatment and in the latter case not properly 50 freeing the fiber because of under-treatment, and in both cases the pulp produced is of such character that the paper made from it is not of as good a grade as the paper made from pulp free from under-digested or over-digested fiber, and particularly as regards 55

the making of paper by the sulfite process, the lack of uniformity of the moisture-content in the chips results in the production of paper of irregular color or shade.

The actual conditions as met in the practice of manufacturing paper pulp, are such as to present relatively great obstacles to be overcome, from a commercial standpoint, to the carrying out of this most desirable manner of treating the materials. It is the common practice to furnish the raw material to the factories where the wood pulp or other material is to be produced, in the form of logs which in the course of their transit to the factory are subjected to the weather and usually have been floated down streams wherein they are exposed to the water for such lengths of time that they become partially water-soaked, and practically invariably each log is water-soaked to a non-uniform degree, the greatest amount of moisture lying at the outer surface of the log and being graduated in moisture-content toward the center thereof, the moisture-content also depending upon the kind of wood of which the log is formed. These logs, in accordance with common practice, are acted upon by chipping machines which reduce them to chips of the desired size, the chipping operations continuing until the log is practically entirely cut away, without regard to the segregation of chips of different moisture-content, as this would be practically impossible from a commercial standpoint. The chips either in their wet condition, or after being subjected to artificial heat to dry them, are then introduced into the chemical solutions. In either event the chips are lacking the characteristic of substantially uniform moisture-content, though they would be drier in the one case than in the other, and because of this fact would be in better condition for the treatment than if not dried at all. Nevertheless the chips which were dried would, because of the non-uniform moisture-content, present the objections as above pointed out.

My primary object, generally stated, is to provide a novel and highly feasible method, from a commercial standpoint, of treating particles of non-uniform moisture-content to an impregnating fluid, to produce a relatively perfect and uniform product, and more especially to improve upon the process of manufacturing paper pulp from wood

chips, to the end that wood pulp may be more economically produced, and be produced of such grade as to improve the product manufactured therefrom.

5 Generally stated, my improvement consists in causing the particles of non-uniform moisture-content and which are to be treated with the impregnating fluid, to remain in contact with each other, preferably after 10 they have been artificially dried, in any suitable container, for a length of time sufficient to cause the moisture in the mass of particles to become substantially equalized throughout the mass, and thereafter subjecting them to the desired impregnating fluid, which in the case of the manufacture of paper pulp would be a digesting fluid which may be the kind usually employed, the equalization above referred to being effected 15 by the damper particles giving up a portion of their moisture and the less damp particles absorbing it, the length of time that the particles are required to remain in contact with each other to produce 20 this result depending upon the degree of moisture in the particles, the character of the particles and the temperature.

Any suitable apparatus for practising 25 my improved method may be employed, certain 30 desirable constructions therefor when the invention is practised in the preferred manner for the manufacture of wood-pulp, being shown in the accompanying drawings wherein:

35 Figure 1 is a view in elevation, and in the nature of a diagram of one form of apparatus suitable for carrying out my improved method, the apparatus shown being more particularly suited for the manufacture of 40 paper pulp and involving a digester for wood chips.

Fig. 2 is a view like Fig. 1 of the digester thereof and adjacent parts, this view being partly sectional.

45 Fig. 3 is a view like Fig. 1 but more in detail and showing certain of the parts in section.

50 Fig. 3^a is a view in sectional elevation and partly broken away, showing a desirable construction of racks for the drier portion of the apparatus.

Fig. 4 is a section taken at the line 4 on Fig. 3 and viewed in the direction of the arrow.

55 Fig. 5 is a view in vertical sectional elevation of a modification of the bin into which the drier discharges.

Fig. 6 is a view like Fig. 1 of another construction of apparatus suitable for carrying 60 out my improved method.

Fig. 7 is a broken view like Fig. 5 taken in a vertical plane in Fig. 6 midway between opposed walls of the bin which is superposed by the drier.

65 Fig. 8 is a view like Fig. 1 of still an-

other form of apparatus by which my improved method may be practised.

Fig. 9 is an enlarged view in vertical section of one of the similar equalizing receptacles of the structure shown in Fig. 8.

Fig. 10 is a view similar to Fig. 1 of still another form of construction by which my improved method may be practised; and

Fig. 11, a plan view of the structure shown in Fig. 10.

The apparatus shown in Figs. 1 to 4 inclusive involves a drier represented at 10 into which the particles to be dried, as for example the wood chips, are introduced and through which they pass and during such passage are subjected to drying currents of air; a bin or receptacle 11 wherein the equalizing of the moisture in the particles, takes place, this bin being in communication with the discharge of the drier 10; a charging bin 12 located above the bin 11 and adapted to receive from the latter, as through the medium of the blower apparatus shown at 11^a, the particles, the moisture-content of which is equalized in the bin 11; and a digester 13 which is supplied with charges of the particles, from the storage bin 12, a valve 12^a being located between the bin 12 and digester 13 and the latter having an outlet-valve 13^a.

The type of drier 10 represented in the drawings is that involving a plurality of uprightly disposed racks 14, the end walls of which are represented at 15 in Fig. 3, 100 these racks extending parallel with each other and having opposed walls open to the passage therethrough of the drying medium, as for example heated air, in accordance with the practice which is common to drying apparatus in general, the said opposed walls of the racks through which the air passes to perform the drying function, being preferably formed of upright series of louvered plates 16 which are so arranged 110 that the plates 16 of one series converge relative to the plates 16 of the opposite series thereof, with the plates spaced apart vertically, as illustrated of the rack in Fig. 3^a. The upper ends of the racks 14 open into 115 a garner, or bin, 17 the bottom of which is formed of a series of angle-shaped plates 18 which are spaced apart and close the bin 17, except to the upper ends of the racks 14, this bin being provided to receive the particles to be dried. The racks 14 contain in 120 their lower portions, feeding devices, represented at 19, these feeding devices being mounted on shafts 20 journaled in the opposite end walls of the racks 14. The feed 125 devices 19 are provided about their peripheries with a series of pockets 21 formed between longitudinally-extending teeth thereon, co-operating with plates 22 to cause the discharge from the racks to be controlled 130

by the rotation of the devices 19, these devices being driven from a shaft 23 carrying bevel pinions 24 which mesh with bevel gears 24^a on the shafts 20.

- 5 The bin 11 is of such construction that in the drawing off of particles therefrom at its lower end to charge the digester 13, the mass of particles will descend therein substantially uniformly, or in other words, all 10 of the particles discharged from this bin will be those which went into the bin first, as distinguished from the commingling of the particles which entered the bin at times relatively remote to each other, this being 15 effected in the construction shown in Fig. 3 by the substantially pyramid-shaped deflector 25 coöperating with the central pyramid-shaped discharge portion 26 of the bin 11, to which portion said deflector is 20 secured to be spaced therefrom and provide a continuous space between the lower edges of the deflector 25 and the adjacent surfaces of the walls of the portion 26 as shown.

In building an apparatus to carry out my 25 improved method it is necessary that it be so constructed that the particles to be subjected to the moisture equalizing process, be permitted to remain in contact with each other prior to the impregnating fluid treatment, as for example in a digester, for a 30 length of time sufficient to produce the desired equalization of the moisture therein, the length of time required for this, manifestly varying with the character of the 35 particles to be treated and the moisture-content thereof. Furthermore the amount of particles drawn from the equalizing portion of the apparatus for treatment and the frequency with which the apparatus is thus 40 drawn on for material, are elements which would be considered in determining the proportions of the apparatus for any particular conditions. For purposes of illustration let it be assumed that it requires 8 hours to 45 digest a charge of wood fiber in the digester 13, and thus requiring three separate charges of particles per day for the continuous operation of the digester, and that the material which is treated in the digester is wood 50 fiber and the particular wood fiber employed requires approximately 16 hours to effect moisture equalization for all practical purposes; the bin 11 would preferably be of such proportions that its capacity would be 55 substantially equal to three times the capacity of the digester 13 and the drier 10 would be of such proportions and so operated that it would insure, by reason of the output of the drier for any given time, the 60 particles remaining in the bin 11 for at least 16 hours. If the drier were a continuously operating element, it would preferably have a capacity for 24 hours of substantially three times that of the digester, under the conditions above stated, but if the drier were of

greater capacity it would be operated intermittently to refill the bin 11 after the equalized particles are drawn therefrom.

In the operation of the apparatus as the charges are dumped from the digester, with 70 an interval of 8 hours between each discharge, and the digester replenished with raw material which preferably is effected through the bin 12 and valve 12^a, so as to accomplish the rapid charging of the digester, the mass of particles in the bin 11 descends therein uniformly in replenishing the supply in the charging bin 12, and in the course of the movement of the particles from the drier 10 to the digester those which 75 later enter as a charge into the digester, are caused to remain in close contact with each other for a length of time sufficient to effect the uniform distribution of the moisture in the particles throughout the mass thereof, 80 the fact that the particles are discharged from the drier in a heated condition, and in such condition are caused to lie in contact with each other causing the dissemination of the moisture throughout the mass to be 85 more quickly effected.

It may be stated that while the apparatus should be so constructed that the particles to be subjected to the fluid-impregnating treatment, should remain in contact with 90 each other for a sufficient length of time to produce the desired degree of moisture equalization, and while from a commercial standpoint and under ordinary conditions it probably would be more economical to 95 cause the particles to contact with each other only for such a length of time as is required to produce the desired moisture equalization, the apparatus may be so constructed or so operated in carrying out my 100 method that the particles may remain in juxtaposed position and in contact with each other for a length of time greater than that required to produce the desired degree of 105 moisture equalization, without effecting any 110 harmful results.

Referring to the structure shown in Fig. 5, this figure is intended to show a slight modification of the bin 11. In this case the means which provide for the uniform lowering of the material in the bin 11 throughout its cross-sectional area as the particles are withdrawn from the opening in its bottom portion 26, instead of being provided of the form shown in Fig. 3, are composed of a plurality of vertical series of deflector plates 27, these plates being of inverted trough form as illustrated. Each alternate series 27 extend at right angles to the series thereof above and below, the deflectors of alternate 115 series extending in the same direction, being staggered as represented, the effect of thus providing the deflectors 27 being that of causing the particles to descend substantially uniformly through the bin 11 when 120 125 130

the particles in the lower portion of the bin are discharged, as distinguished from the particles at the upper portion of the mass pouring down through the center of the mass.

The arrangement shown in Fig. 6 is the same as that disclosed in Figs. 1 to 4 inclusive except as to the equalizing bin, which in the constructions shown in Figs. 6 and 7 is represented at 28. This bin receives the dried particles from the superposed drier 10 as in the case of the previously described structure, but instead of being formed as an open structure, is provided with three separate compartments 29, 30 and 31, which in the case of the illustration given in connection with the description of the structure shown in Fig. 1, would each hold an amount of material substantially equal to the capacity of the digester 13. The bottoms of the compartments 29 and 30 are hopper-shaped as indicated at 32 in Fig. 7, the discharge portions 33 of these hoppers being controlled by pivotally supported valves 34 which, in the position of the parts shown in Fig. 7 prevent the flow of material through them, these valves being connected with any suitable operating mechanism (not shown) for shifting them into and out of closed position. The bottom of the compartment 31 is of hopper shape as illustrated at 35 and opens into the blower apparatus 11^a.

In the operation of the apparatus of Figs. 6 and 7, the valves 34 co-operating with the bottoms of the compartments 29 and 30 are alternately operated, after withdrawing the particles from the compartment 31, to lower the particles in the compartment 30 into the compartment 31 and the particles in the compartment 29 into the compartment 30, the effect of this operation being to insure the uniform passage of the particles through the bin 28 so that each particle will remain therein substantially for the same length of time as every other particle to produce the moisture equalization desired.

The apparatus shown in Figs. 8 and 9 differs from that hereinbefore described primarily in the fact that the equalizing bins instead of being located below the drier 10, are located directly above the digesters which are to be fed therefrom. In the case of this apparatus the drier represented at 10 is connected with the blower mechanism 11^a which, when the drier is a continuously discharging structure, operates continuously to force the dried and heated particles from the drier 10 upwardly through the pipe 11^b from which they discharge through the branches 11^c thereof into the upper inlet ends of the equalizing bins, indicated in these figures at 36, these equalizing bins being provided in duplicate and each superposed on and opening into a digester 13 located below it, with valves 13^a controlling

the discharge of the particles from the bins 36 into the digesters.

The bins 36 which are so constructed in any suitable way, as by the vertical series of inverted trough-shaped cross-pieces 37 as explained of the construction in Fig. 5, to insure the uniform lowering of the particles in these bins during the drawing off of particles therefrom at their lower ends, should be so proportioned that in the operation of the apparatus the particles to be treated in the digesters 13 will remain in the bins 36 a sufficient length of time to effect the equalization of the moisture therein to the desired degree. The comments herein made as to the various conditions affecting this matter of equalization, apply to the apparatus now being explained and it will therefore be sufficient to say that, assuming the particular case upon the basis of which the structure of Figs. 1 to 4 inclusive was described, the bins 36 should each be of substantially three times the capacity of the digester which is charged therefrom, and the drier 10 should be of such capacity that it will supply the dried particles to the bins 36 in such amounts as to insure all of the particles discharged from the bins 36 into the digesters 13, being in contact with each other for the length of time necessary to produce the desired moisture equalization namely in the particular example illustrated 16 hours.

In the construction illustrated in Figs. 10 and 11, a battery of equalizing bins are provided, these bins being drawn upon successively to furnish the charges of particles to the digesters which are shown as two in number, instead of providing a single bin and drawing a portion of the contents of this bin each time the digesters are to be charged.

In this arrangement the equalizing bins are represented at 37, 38 and 39, these bins being connected at their upper ends through the medium of branch pipes 40, 41 and 42 with a pipe 43 opening into the blower 11^a which connects with the discharge portion of the drier 10, the branches 40, 41 and 42 having valves 43 therein. The lower discharge ends of the bins 37, 38 and 39 connect with branch pipes 44, 45 and 46 respectively, these pipes containing valves 47 and uniting with a pipe 48 connected with a blower 49, the outlet end of which is connected with a pipe 50 which is provided at its upper end with branches 51 opening into the upper ends of receiving bins 12 like the bin 12 of Fig. 1, these bins being located over the digesters 13 and discharging into the latter respectively through the valved portions 12^a. It will be understood from the foregoing that the course of the particles is through the drier 10, thence by the suction means 11^a into the equalizing bin section of the apparatus, thence to the receiving 130

bins 12 under the action of the blower 49, and then into the digesters 13.

In accordance with the general arrangement shown in these figures, the idea is to cause the particles after leaving the drier 10 to remain in the respective bins 37, 38 and 39 for such a length of time as will insure the effecting of the desired degree of moisture equalization before the particles 10 pass into the digesters 13. This arrangement is laid out upon the assumptions given by way of example in connection with the description of the construction shown in Figs. 1 to 4 inclusive namely that it requires 15 about 8 hours to digest a charge of wood fiber in the digesters, that it requires approximately 16 hours to effect moisture equalization for all practical purposes and that the apparatus is in continuous operation, and upon these assumptions by way of example, each of the bins 37, 38 and 39 would have substantially the same capacity as the two digesters 13 combined, or in other words a charge from any one of the said 20 bins would be sufficient to charge both digesters, though it will be understood that if desired, but one digester may be employed in which case the capacity of each of said equalizing bins would be reduced substantially one-half, or a battery of more digesters may be employed in which case the capacity of the equalizing bins would be correspondingly increased.

In the operation of the apparatus, the 25 particles as they are discharged from the drier 10 are, by manipulating the valves 48, introduced into one of the equalizing bins which supplied the charge then being operated on in the digesters 13, and as the bins 37, 38 and 39 are successively emptied of 30 their contents to charge the digesters 13, the valves 48 are manipulated to fill these bins as they become empty. It will thus be understood that upon the particular basis 45 of operation and assumption of conditions as above stated, all of the particles in any one of the bins 37, 38 and 39 will remain therein for at least 16 hours, some of them remaining longer as will be manifest, this 50 being sufficient to equalize the moisture-content to the desired degree.

In practising my improved method I prefer to provide for the equalization of the moisture-content of the particles of material, under heat, inasmuch as thereby the 55 equalizing step is performed more rapidly than if the particles of material were allowed to be in contact with each other when in unheated condition, this equalizing in the 60 presence of heat being most efficiently accomplished in apparatus wherein the drier is above the equalizer-receptacle and discharges directly thereto, as in the case of certain of the constructions illustrated in 65 the accompanying drawings.

It will be understood from the foregoing that in all of the forms of apparatus shown and described, provision is made for causing the particles of material and which are of non-uniform moisture-content, to remain 70 in contact with each other a sufficient length of time to cause the moisture in the particles to be substantially equalized, before the particles are presented for further treatment, as for example in the digesters, and 75 while the particular forms of apparatus shown and described are desirable for carrying out my invention, it will be readily understood that my invention may be practised by such apparatus in modified or 80 changed condition and furthermore by any other suitable apparatus.

Furthermore while I have described my invention for the manufacture of wood pulp, I do not wish to be understood as 85 intending to limit it thereto as it may be used where it is desired that impregnating fluids, other than those required for digesting wood fiber be employed.

What I claim as new and desire to secure 90 by Letters Patent is:—

1. The process of treating to an impregnating fluid pieces of material of non-uniform moisture-content requiring substantial uniformity of moisture-content for uniformity of treatment thereof by the impregnating fluid, which consists in causing the pieces of non-uniform moisture-content to be in contact with each other for a length 100 of time sufficient to effect substantially uniform dissemination through the pieces of the moisture therein, to substantially equalize the moisture-content of the pieces, and subsequently thereto treating the pieces to the impregnating fluid. 105

2. The process of treating to an impregnating fluid pieces of material of non-uniform moisture-content requiring substantial uniformity of moisture-content for uniformity of treatment thereof by the impregnating fluid, which consists in causing the pieces of non-uniform moisture-content to be in contact with each other in a closed container for a length of time sufficient to effect substantially uniform dissemination 110 through the pieces, of the moisture therein, to substantially equalize the moisture-content of the pieces, and subsequently thereto treating the pieces to the impregnating fluid. 115

3. The process of treating to an impregnating fluid pieces of material of non-uniform moisture-content requiring substantial uniformity of moisture-content for uniformity of treatment thereof by the impregnating fluid, which consists in subjecting the pieces of non-uniform moisture-content to a drying operation for partially drying said pieces to a non-uniform moisture-content, thereafter causing the pieces of non- 125

- uniform moisture-content to be in contact with each other for a length of time sufficient to effect substantially uniform dissemination through the pieces of the moisture therein, to substantially equalize the moisture-content of the pieces, and subsequently thereto treating the pieces to the impregnating fluid.
4. The process of treating to an impregnating fluid pieces of material of non-uniform moisture-content requiring substantial uniformity of moisture-content for uniformity of treatment thereof by the impregnating fluid, which consists in subjecting the pieces of non-uniform moisture-content to a drying operation for partially drying said pieces to non-uniform moisture-content, thereafter causing the pieces of non-uniform moisture-content, and while in heated condition to be in contact with each other for a length of time sufficient to effect substantially uniform dissemination through the pieces of the moisture therein, to substantially equalize the moisture-content of the pieces, and subsequently thereto treating the pieces to the impregnating fluid.
5. The process of treating to an impregnating fluid pieces of material of non-uniform moisture-content requiring substantial uniformity of moisture-content for uniformity of treatment thereof by the impregnating fluid, which consists in feeding the pieces of non-uniform moisture-content through a predetermined path and simultaneously therewith subjecting them to heat for partially drying the pieces to a non-uniform moisture-content, discharging said pieces into a container and maintaining them therein in close contact with each other for a length of time sufficient to effect substantial dissemination of the moisture through the pieces, and thereafter treating the pieces to the impregnating fluid.
6. The process of treating to an impregnating fluid pieces of material of non-uniform moisture-content requiring substantial uniformity of moisture-content for uniformity of treatment thereof by the impregnating fluid, which consists in causing the pieces to travel in a continuous course and in traveling such course to be first subjected to a drying operation for partially drying the pieces to a non-uniform moisture-content, thereafter causing the pieces to be maintained in relatively close contact with each other for a length of time sufficient to effect substantial dissemination of the moisture through the pieces, thereafter treating the pieces to the impregnating fluid.
7. The art of manufacturing wood pulp from pieces of wood fiber of non-uniform moisture-content, which consists in causing the pieces of wood fiber of non-uniform moisture-content to be in contact with each other for a length of time sufficient to effect substantially uniform dissemination through the pieces of the moisture therein, to substantially equalize the moisture-content of the pieces, and subsequently thereto subjecting the said pieces to fluid treatment for reducing them to wood pulp.
8. The art of manufacturing wood pulp from pieces of wood fiber of non-uniform moisture-content, which consists in subjecting the pieces of wood fiber of non-uniform moisture-content to a drying operation for partially drying said pieces to a non-uniform moisture-content, thereafter causing the pieces of non-uniform moisture content to be in contact with each other for a length of time sufficient to effect substantially uniform dissemination through the pieces of the moisture therein, to substantially equalize the moisture-content of the pieces, and thereafter subjecting the said pieces to fluid treatment for reducing them to wood pulp.
9. The art of manufacturing wood pulp from pieces of wood fiber of non-uniform moisture-content, which consists in subjecting the pieces of wood fiber of non-uniform moisture-content to heat for partially drying said pieces to a non-uniform moisture-content thereafter causing the partially dried pieces of non-uniform moisture-content to be in contact with each other, while in heated condition, for a length of time sufficient to effect substantially uniform dissemination through the pieces of the moisture therein, to substantially equalize the moisture-content of the pieces, and subsequently thereto subjecting the said pieces to fluid treatment for reducing them to wood pulp.

GEORGE H. HESS.
